UNITED STATES PATENT OFFICE.

JAMES P. MANLEY, OF ANDERSON, INDIANA.

RAILWAY-TIE.

1,299,202.

Specification of Letters Patent.

Patented Apr. 1, 1919.

Application filed March 26, 1917, Serial No 157,480. Renewed February 28, 1919. Serial No. 279,456.

To all whom it may concern:

Be it known that I, JAMES P. MANLEY, a citizen of the United States, residing at Anderson, in the county of Madison and State of Indiana, have invented certain new and useful Improvements in Railway-Ties; and I do declare the following to be a full, clear, and exact description of the invention, such as will enable others skilled in the art 10 to which it appertains to make and use the same.

My invention relates to improvements in rail ties and fasteners, but more particularly to an improved form of rail chair carried 15 by the end of the tie.

The object of the invention is to so construct the chair as to permit it to be stamped from a single rectangular malleable plate, thus insuring that the device shall be manufactured at a small cost regardless of the 20 fact that it will be highly efficient.

With the foregoing general object in view, the invention resides in the novel features of construction to be hereinafter fully described and claimed, the descriptive matter 25 being supplemented by the accompanying drawing which constitutes a part of this specification and in which:

Figure 1 is a plan view of a plate stamped 30 into the proper shape for constructing one of the improved chairs;

Fig. 2 is a plan view of a complete chair made from the plate shown in Fig. 1;

Fig. 3 is an edge view of a pair of chairs 35 such as that depicted in Fig. 2 secured to the ends of a tie plate and showing a pair of rails clamped in said chairs;

Fig. 4 is a plan view of one end of Fig. 3; and Fig. 5 is an edge elevation of a pair 40 of chairs showing the manner in which they may be formed on the ends of the tie plate.

In Figs. 1 to 4 of the drawings above briefly described, the numeral 1 designates a rectangular plate of malleable iron or 45 steel, the side edges of said plate, near one end thereof having elongated notches 2 whose inner edges are parallel with said edges of the plate. The ends of the notches 2 are undercut as shown at 3 for a purpose 50 to appear. The edge portions 4 of the plate 1, between one end of the notches 3 and the adjacent end of said plate are bent upwardly on lines 5 parallel with the side edges of the plate and form outer abutments, the

corners of said portions being preferably 55 removed as shown.

The edge portions 6 of the plate 1 at the ends of the notches 2 opposite the portions 4, are bent upwardly on oblique lines 7 leading from the inner edges of said notches to 60 the edges of the plate, and these last named portions constitute additional abutments. The undercut ends 3 of the notches 2 form undercut inner ends for the several abutments 4 and 6.

As shown in Fig. 3, a pair of chairs constructed as described may be secured by bolts or the like 8 to the ends of a tie plate 9, or the chairs may be formed by stamping the ends of a tie plate 9^a as above described 70 and bending outer and inner abutments 4^a and 6^a upwardly therefrom. (See Fig. 5.) Whether the improved chairs be constructed separate from or integrally with the tie plates, wedges 10 will be driven between the 75 edges of the rails and the inner and outer abutments as depicted in Figs. 3 and 4, each of said wedges having a base 11 to underlie the rail and a flange 12 to overlie the base of the latter. A series of openings 13 are 80 preferably formed at the contracted end of each wedge in order that keys 14 may be driven therethrough for contact with one edge of the chair to prevent displacement of the wedge after it has been driven. The 85 keys in question may be driven either through the openings 13 or through notches 15 in the outer edges of the wedges, and if the latter course is adopted, said keys will be received in openings 16 in the chair. 90 Either or both of these fastening means for the wedges may be employed, and in fact any other suitable arrangement for this purpose could be used.

From the foregoing, taken in connection 95 with the accompanying drawing, it will be observed that the invention is of simple and inexpensive nature, yet that it will effectively hold the rails against creeping or spreading. On account of these advantages, 100 the specific construction shown constitutes the preferred form of the device, but I wish it understood that within the scope of the invention as claimed, numerous minor changes may be made without sacrificing the principal advantages.

I claim:

A rail chair comprising a malleable base

plate having near one end a pair of opposed elongated notches in its side edges formed with undercut ends, the edge portions of said plate between said notches and said end 5 of the plate being bent upwardly on lines parallel with said edges of the plate, the edge portions of said plate at the other end of the notches being bent upwardly on oblique lines leading from the inner edges of 10 said notches to the edges of the plate, all of

said upwardly bent portions constituting abutments whose inner ends are formed by said undercut ends of the notches.

In testimony whereof I have hereunto set my hand in the presence of two subscribing 15 witnesses.

JAMES P. MANLEY.
